UNITED STATES PATENT OFFICE.

EDWARD J. KILEY, OF MANSFIELD, OHIO, ASSIGNOR TO THE OHIO BRASS COMPANY,
OF MANSFIELD, OHIO, A CORPORATION OF OHIO.

VALVE.

Application filed May 11, 1922. Serial No. 560,055.

To all whom it may concern:

Be it known that I, EDWARD J. KILEY, a citizen of the United States of America, residing at Mansfield, in the county of Rich-
land and State of Ohio, have invented cer-
tain new and useful Improvements in
Valves, of which the following is a speci-
fication.

My invention relates to valves and more
particularly to the disc holder of the valve,
by means of which the disc proper is main-
tained in position.

The object of my invention is to produce
a simple, efficient and economical disc holder
whereby the disc proper may be removed
from time to time as its face, which comes
in contact with the valve seat, may become
worn.

My invention resides in the construction,
combination and relation of the various
parts more fully described hereinafter.

In the drawings accompanying this speci-
fication—

Figure 1 is a bottom plan view of the cup
portion of my disc holder.

Fig. 2 is a sectional view of Fig. 1 on the
line 2—2.

Fig. 3 is a top plan view of the cup por-
tion or member.

Fig. 4 is a top plan view of a washer
member which I employ.

Fig. 5 is a sectional view of Fig. 4 on
the line 5—5.

Fig. 6 is a plan view, top or bottom, of
the disc proper which is usually of composi-
tion of varying properties to meet require-
ments.

Fig. 7 is a side view of the disc shown in
Fig. 6.

Fig. 8 is a side elevation of my disc
holder and disc proper in partial section.

Fig. 9 is a top view of Fig. 8.

Fig. 10 is a bottom view of Fig. 8.

In the improved construction embodying
my invention I employ a cup member 1
which I form up out of sheet metal such
as phosphor bronze, brass, steel or copper
or other similar or suitable material. The
process of forming up the cup member 1 is
that usually employed in similar work of
stamping, spinning, drawing, etc., and
which operation is brought about by a
variety of processes well known to those
skilled in the art.

The finished member 1 is provided with a

raised boss 2 and having an opening 3 in
the face of the boss. The opening 3 is for
the reception of the stem 4 of the valve.
The boss 2 is so formed as to provide a
shoulder 5 against which the flange 6 on
the stem 4 engages. The side wall or flange
7 is provided with a plurality of slots 8
thereby cutting the side wall or flange into
a plurality of segments forming a circle
and each segment having a certain amount
of resiliency, which would not be the case
if the slots 8 were not present. The outer
edge of the side wall or flange is provided
with a turned-in shoulder 9 to engage with
and hold the composition disc 10 in posi-
tion.

I also employ a washer member 11 which
is formed up out of steel, copper, brass,
etc., which is positioned within the cup
member 1 as shown in Fig. 8. The washer
11 takes the downward thrust of the stem
4 when the valve is in a closed position, and
as this thrust may be very severe, the mem-
ber 11 is made quite heavy as compared
with the cup member, and in order to re-
duce the thickness of the material used in
the washer 11, but to maintain its strength
I shape the member 11 as shown in Fig. 5
by producing a boss 12 thereon. This boss
being hollow on the under side next to the
composition disc, no strain or pressure is
exerted upon the center of the composition
disc, but the pressure is transmitted to that
portion of the composition disc which is
directly over the valve seat and, therefore,
the composition disc is not subjected to any
torsional or bending stresses, but only to
direct compressive stresses.

In assembling my invention the cup mem-
ber 1 is first placed upon the stem 4 and in
engagement with the flange 6 on the stem.
The washer 11 is then placed in position
and the composition disc is then sprung into
position. If the parts have been properly
formed to size, the lip 9 on the various seg-
ments forming the side walls of the cup
member will engage and press against the
edge of the composition disc, thereby hold-
ing the parts securely in position and en-
gagement with each other through the re-
siliency of the segments forming the side
walls of the cup.

It will be readily understood that one of
the advantages of my invention is the fact
that the disc 10 can at any time be readily

removed if necessary and replaced with a new composition disc. It will also be evident that various modifications of my improved disc and holder will suggest themselves to those skilled in the art and, therefore, I do not wish to be limited otherwise than by the following claims.

Claims—

1. A disc holder for a valve disc comprising a cup shaped member, the side of the cup member formed of a plurality of segments to yieldingly grip a disc and maintain it within the member, means on the cup member to receive the end of an operating stem and means in the cup member to receive the thrust of the stem in closing the valve.
2. A disc holder for a valve disc comprising a cup shaped member the side of which is formed of a plurality of resilient segments and having means on the edge of said segments to maintain the disc in position within the cup member and means for attaching the cup member to an operating stem.
3. A valve comprising a cup shaped member having a segmented resilient side wall and having means on the edge of the wall to engage and hold a disc, a disc positioned within the cup member and held by said wall and means, means on the cup member to receive an operating stem and secure the cup member to the stem and means to transmit the thrust of the stem to the disc.
4. A valve comprising a cup shaped member having a resilient side wall formed of a plurality of segments, a disc positioned within the cup member, means on the cup member to receive an operating stem and secure the cup member to the stem and means to transmit the thrust of the stem to the disc, and means on the side wall to retain the parts together.
5. A valve comprising a cup shaped member provided with a recessed boss to receive a headed operating stem and a resilient side wall comprising a plurality of segments, a disc positioned in the cup member to engage the seat in a valve, means interposed between the head of the stem and disc to impart thrust from the stem to the disc,

and means on the edge of the segments to hold the parts in position, but permit the disc to be removed from the cup member at will.

6. A valve comprising a cup shaped member provided with a recessed boss to receive a headed operating stem and a resilient side wall comprising a plurality of segments, a disc positioned in the cup member to engage the seat in a valve, interposed means between the stem and disc to impart thrust from the stem to the disc, means on the interposed means projecting into the recessed boss and engaging the head of the stem for applying the thrust from the stem to the outer portion of the interposed means and means on the edge of the segments of the side wall to hold the parts in position, but permit the disc to be removed from the cup member at will.

7. A valve comprising a cup shaped member, means on the member to receive the end of a valve stem, means on the stem to engage the means on the member to limit the relative movement of the member and stem in one direction, a disc positioned within the member to engage a valve seat, means interposed between the stem and disc to distribute the thrust of the stem over the surface of the disc and turned over means on the member to engage the edge of the disc and maintain the parts in a fixed relative position.

8. A valve comprising a cup shaped member, a disc received in said member to engage a valve seat, means formed up out of the member to receive the end of a valve stem, integrally formed means on the stem engaging the member for moving the member and disc in one direction when the stem is moved in that direction and means within the cup shaped member engaging the disc and stem to move the disc and member in the opposite direction when the stem is moved in the opposite direction and means to maintain the parts in an assembled relation.

In testimony whereof I affix my signature.

EDWARD J. KILEY.
